COMPUTER

William M. Rader, Hoven, S. D.

Application December 16, 1944, Serial No. 568,523

2 Claims. (Cl. 235—86)

1

This invention relates to computing devices. It is a general object of the invention to provide means for quickly and accurately computing results from a table or tables of figures to eliminate time consuming and frequently inaccurate computation with pencil and paper.

More particularly it is an object of the invention to provide a mechanical computer of simple construction wherein the device can be operated to shift a movable factor table relative to one or more stationary factor tables in accordance with the computation desired and wherein such movement will accurately and quickly disclose the desired result.

These and other objects and advantages of the invention will more fully appear from the following description made in connection with the accompanying drawings, wherein like reference characters refer to the same parts throughout the views, and in which:

Figure 1 is a plan view of an embodiment of the invention;

Figure 2 is an end elevation thereof; and

Figure 3 is an enlarged fragmentary sectional view of one of the stationary factor elements and the movable web.

The apparatus includes a baseboard 4 having one edge thereof secured to an upright back 5 with the baseboard preferably slanting as shown in Figure 2. Mounted across the lower end of the baseboard 4 is a reel 6 rotatably supported by brackets 7 suitably secured to the baseboard 4 and supporting the ends of the reel shaft 8. As shown in Figure 1, spring washers 9 are interposed between the ends of the reel 6 and the reel supporting brackets 7 to provide a slight frictional drag on the reels 6 so that they will not move about the axes accidentally but can be turned freely by rotating the crank handles 10 secured on the ends of the reel shaft 8.

Extending across an upper intermediate portion of the baseboard 4 is a reel 11 supported by brackets 12 which are adapted to receive the reel shaft 13, the latter having cranks 14 on its ends. Spring washers 15 similar to the washers 9 on the reel unit first described are also provided to produce a slight frictional drag on the reel 11.

Located above the intermediately disposed reel 11 is a third reel 16 having a shaft 17 supported by brackets 18. A web 19 has one end thereof wound about the lower reel 6 and has its other end wound about the intermediate reel 11, the web being extended about the idler reel 16 at the upper side of the baseboard 4. As a result that portion of the web 19 between reels 6 and 55

2

gives the operator a view of one side of the web 19 and that portion of the web extending between and lying over the reel 11 and the idler reel 16 giving the operator a view of the opposite side of the web from that side exposed between reels 6 and 11.

On the right hand end of the reel shaft 8 is a sprocket 20 and a second sprocket 21 is mounted on a stub shaft 22 extending out of the right hand edge of the baseboard 4. A chain 23 extends between the sprockets 20 and 21 and the chain carries an outwardly projecting pin 24 which is adapted to engage a stop element 25 extending from the edge of the baseboard 4 adjacent the sprocket 21. As a result the reel 6 can be rotated a number of revolutions in either direction between the limits of movement of the pin 24 on the chain 23 on one side of the stop 25 to the other.

Between the reels 6 and 11 is a bar 26 having downward extensions 27 across its ends so that the major portion of the underside of said bar 26 is elevated slightly from the upper surface of the baseboard 4. Across each end of the bar 26 is a retainer 28 having one end secured to the baseboard as by a screw 29 and having its other end adjustably connected to the baseboard by a nutted bolt 30. By means of this structure the bar 26 can be shifted slightly up or down the slant of the baseboard 4 and can be clamped in the desired adjusted position. This is done to permit the ready assembling of the apparatus and the exactly proper setting of the bar 26 relative to the lines on the web 19. The webs are not always precisely uniform and they are subject to some small changes in linear dimensions. When the latter occurs the apparatus can be quickly and easily corrected.

A flat plate 31 is secured to the top edge of the upright back element 5 and said plate 31 extends over the idler reel 16 and is provided with a free edge 32 lying across and closely adjacent the web 19.

Referring to Figure 1 the bar 26 is provided with indicia extending thereacross and it is shown bearing numbers "1-1," "1-15," "2-1," "2-15," etc., to "12-15" at the right hand end of the bar. That side of the web 19 which is exposed between the reels 6 and 11 is provided with longitudinal rows of numerals, the first row at the left hand side bearing sets of numerals "3-31," "4-1," and "4-2" reading upwardly from the stationary bar 26. The second longitudinal row of numerals on that face of the web 19 reads "4-14," "4-15," "4-16," reading upwardly from the bar

26 and above the numerals "1-15" on said bar 26. The sets of numerals on the stationary bar 26 represent days of the month such as January 1, January 15, and February 1 in the first three sets of numerals reading from the left. The sets of numerals on the face of the web 19 which were quoted above also represent dates, those three sets in the vertical row at the left being March 31, April 1 and April 2. The stationary plate 31 which extends from the vertical back element 5 10 is provided with numbered spaces therealong and across the width of the web 19 the numerals being in units from "1 to 10," in tens from "10 to 100" and in hundreds from "100 to 1000." In the illustrated example these numbers represent the amounts of principal upon which interest rates are to be reckoned. That portion of the web 19 which extends between the upper portions 15 of the reels 11 and 16 is a portion of the opposite side of the web from that side bearing the dates adjacent the stationary bar 26. This second side of the web 19 bears longitudinally arranged rows of figures representing amounts of interest.

The figures on the drawings are arranged for computation of interest on different amounts of money at a rate of six per cent (6%). For instance, the apparatus has been set so that the date on the web 19 immediately adjacent the date "1-1" or January 1 on the stationary bar 26 is "3-31" representing March 31. The device would be so set to determine interest for the ninety day period from January 1 to March 31. If the amount borrowed is one hundred dollars (\$100) the operator notes the number "100" on the stationary plate 31 at the upper side of the apparatus and the amount of interest is indicated immediately therebelow on the opposite side of the web 19, the amount shown being \$1.50. At the right hand end of the bar 26 is the date "12-15" and immediately thereabove on the web 19 is the date "3-14." This indicates another ninety day period and, of course, the amount of interest on the \$100 principal would be the same. Only a comparatively few sets of dates have been shown on the web 19 and related sets of interest figures have also been shown to illustrate the invention. Naturally, the rows of dates extending longitudinally of the web 19 would be carried out to provide complete sets of dates for the entire year.

I have shown the dates on the bar 26 as representing the first and middle of each month. Of

course, if the device is made wider months can be subdivided more than shown in the drawings.

It should be noted that each column of dates extending longitudinally of the web is intended 5 to be carried out consecutively for all the dates in the year and that the interest columns are carried out so that it is possible to figure from any date on the stationary bar 26 to any day of the year and the proper amount of interest at the predetermined rate will be indicated on the interest table side of the web 19.

Should it be desired to figure interest from January 5, which does not appear on the bar 26, to any desired date in the year the date in question would be moved to the position occupied by March 31 in the drawings immediately adjacent January 1 on the bar 26, and the operator would then note the principal which might be \$100. The interest bearing portion of the web 19 would be wound toward the operator four spaces beyond the space bearing the interest figure \$1.50 in the drawings to give the correct amount of interest from January 5 to the date desired.

It will, of course, be understood that various changes may be made in the form, details, arrangement and proportions of the various parts without departing from the scope of my invention.

What I claim is:

1. In a computer, an idler reel, a pair of winding reels having opposite ends of a web wound thereupon, one of said winding reels being disposed between the other of said winding reels and said idler reel, said web passing from one of said 35 winding reels about the idler reel and thence to the other of said winding reels, whereby portions of opposite sides of said web are exposed to view, indicia on each side of said web, all of said reels lying in substantially the same axial plane, and a pair of relatively stationary elements having indicia thereon, one of said stationary elements being disposed adjacent the exposed portion of one side of said web, and the other of said stationary elements being positioned adjacent the exposed 40 portion of the other side of said web.
2. The structure in claim 1, and the axes of said reels being fixed, one of said stationary elements being adjustably shiftable longitudinally of said web, and means for clamping said last mentioned element against accidental displacement.

WILLIAM M. RADER.
